CLAIM

The ornamental design for a monitor, as shown and described.

DESCRIPTION

FIG. 1 is a front perspective view of a monitor showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion in FIG. 1;

FIG. 10 is an enlarged view of the encircled portion in FIG. 3;

FIG. 11 is an enlarged view of the encircled portion in FIG. 5;

FIG. 12 is an enlarged view of the encircled portion in FIG. 8;

FIG. 13 is a front view of the monitor shown in an example environment of use where the monitor is attached to another monitor to its right side;

FIG. 14 is a front view of the monitor shown in an example environment of use where the monitor is attached to another monitor to its left side;

FIG. 15 is a front perspective view of the monitor shown in an example environment of use where the monitor is attached to another monitor to its left side; and,

FIG. 16 is a front perspective view of the monitor shown in an example environment of use where the monitor is attached to other monitors to its right and left sides.

(Continued)

The evenly-dashed broken lines in the figures depict portions of the monitor that form no part of the claimed design. The evenly-dashed broken lines illustrating environmental structure in FIGS. 13-16 form no part of the claimed design. The dot-dash broken lines encircling portions of the claimed design that are illustrated in enlargements form no part of the claimed design.
